UNITED STATES PATENT OFFICE.

CHARLES H. DAVIS, OF VALLEY CITY, NORTH DAKOTA.

FUEL-PRESS.

1,400,212.

Specification of Letters Patent. Patented Dec. 13, 1921.

Application filed June 21, 1920. Serial No. 390,815.

To all whom it may concern:

Be it known that I, CHARLES H. DAVIS, a citizen of the United States, residing at Valley City, in the county of Barnes and State 5 of North Dakota, have invented certain new and useful Improvements in Fuel-Presses; and I do hereby declare the following to be a full, clear, and exact description of the invention, such as will enable others skilled 10 in the art to which it appertains to make and use the same.

My present invention has for its object to provide an extremely simple and highly efficient fuel press for use in the manufacture 15 of briquets. The improved fuel press is intended for general use, but especially adapted in manufacturing briquets from the waste in fiber factories.

To the above end, the invention consists 20 of the novel devices and combinations of devices hereinafter described and defined in the claim.

In the accompanying drawings, which 25 illustrate the invention, like characters indicate like parts throughout the several views.

Referring to the drawings:

Figure 1 is a plan view of the improved fuel press;

Fig. 2 is a side elevation of the same;

Fig. 3 is a transverse section taken on the line 3—3 of Fig. 1;

Fig. 4 is a longitudinal section taken on the line 4—4 of Fig. 1, on an enlarged scale; and

Fig. 5 is an end elevation of the parts shown in Fig. 4.

The frame of the improved fuel press includes two laterally spaced side members in the form of connected channel bars 6, the 40 flanges of which are turned outward. These side members or bars 6 support a heavy rectangular one-piece die-block 7 mounted between vertically spaced pairs of angle bars 8 rigidly bolted to said side members and the die-block. Extending longitudinally 45 through the die-block 7, from the one end to the other, are, as shown, three laterally and horizontally spaced die seats 9. Rigidly secured in each die seat 9, by pressure or otherwise, is a bushing 10, which extends the full length of the die seat and out of the delivery end thereof. The projecting 50 delivery ends of the bushing 10 are externally tapered and longitudinally split at 11 at circumferentially spaced points. The tapered ends of the bushings 10 are provided

with screw-threads at 12 to receive correspondingly tapered nuts 13 for contracting the delivery end of said bushings.

Longitudinally extended rectangular feed 60 passageways 14 are formed in the top of the die-block 7 and bushing 10, near the receiving end of said bushings. Materials from which the briquets are formed, are delivered into the feed passageways 14 by 65 means of a hopper or other suitable means, not shown. Plungers 15 are mounted in the bushings 10 and secured to a cross head 16 mounted between the vertically spaced 70 pairs of angle bars 8, which act as guide rails therefor, and said cross head is also held by the side members 6 for straight-line sliding movement.

The following connections are provided 75 for operating the cross head 16, to wit:

Journaled in bearings 17, on the side members 6, is a driven shaft 18 having keyed to its intermediate portion, between the side members 6, a pulley 19, over which runs a driving belt, not shown. The ends of the 80 shaft 18 are extended outward of the side members 6 and have keyed to each end thereof a fly-wheel 20, between which and the respective side members 6 is keyed a pinion 21. A counter-shaft 22 is journaled in the 85 bearings 17, and keyed to the ends thereof are gears 23, which mesh with the pinion 21. To the intermediate portion of the shaft 22, between the side members 6, is keyed a pair of pinions 24, which mesh with a pair of 90 relatively large gears 25, each of which is provided with an outwardly extended trunnion 26 journaled in bearings 27 bolted to the webs of the side members 6 and extend through apertures formed therein. 95

The gears 25 are connected by an eccentrically located pin 28, in which is secured one end of a connecting rod 29. The other end of the connecting rod 29 is extended between a pair of transversely spaced lugs 100 30 on the cross head 16 and connected thereto by a pin 31. The forward stroke of the cross head 16 is such as to cause the plungers 15 to travel completely through the feed passageway 14 and project materially into 105 the bushings 10 forward of said passageways.

Obviously, the above described driving connections, from the driven shaft 18 to the connection rod 29, are arranged to balance 110 the pressure delivered to the cross head 16 and thereby cause the same to impart true

straight-line movement to the plungers 15 in the bushings 10 to prevent the same from binding or causing undue friction.

During the forward movement of the plungers 15, portions of the materials in the feed passageways 14 will be forced into the forward portions of the bushings 10 and compressed to form briquets Z. At the completion of each forward stroke of the plungers 15, three briquets are formed, one in each bushing 10, and likewise, three of the completed briquets are forced through or from the contracted delivery ends of said bushing.

15 It will be noted that the length of the bushings 10 is such as to hold a plurality of formed briquets Z, and the friction between the briquets and the bushings, which is materially increased by the contracted 20 ends of said bushings, is such as to retard the movement of the briquets during the forward stroke of the cross head, so that they act as abutments, against which other briquets are successively formed.

25 Obviously, by adjusting the nubs 13, the delivery ends of the bushings 10 may be contracted, at will. In case the bushings 10 wear out, new ones may be substituted therefor.

30 The waste material from which the briquets are formed, is first ground, before de-

livered into the bushings 10, and when the waste from hemp is used in making briquets, the ground waste is sprayed with hot tar or other suitable material to form a binder. 35 When the waste from flax is used in making briquets, the natural oil therein is brought to the surface under the pressure produced thereon by the plungers 15, and which oil acts as a binder for the briquets. Straw or 40 other material may also be used in the improved fuel press for making briquets.

The above described invention has, in actual usage, proven highly efficient for the purpose had in view.

45 What I claim is:

In a fuel press, the combination with a die-block having a die seat, of a bushing in the die seat with its delivery end free and extended outward thereof, said delivery end 50 of the bushing being tapered and longitudinally split, a nut having screw-threaded engagement with the tapered end of the bushing for contracting the same, a plunger working in the bushing, and means for operating the plunger.

55 In testimony whereof I affix my signature in presence of a witness.

CHARLES H. DAVIS.

Witness:

R. T. HEALY.
